PROCESS FOR PRODUCING ACETALDOL

Louis Alhéritière, Beau-Sceil, Melle, France, assignor to Les Usines de Melle (Societe Anonyme), Saint-Léger-les-Melle, France, a corporation of France

**Application February 10, 1947, Serial No. 727,491
In France February 18, 1946**

6 Claims. (Cl. 260—602)

11

This invention relates to a process and apparatus for manufacture of acetaldehyde condensation products and more particularly for the production of aldol and crotonaldehyde.

It is known that the condensation of acetaldehyde with itself to produce aldol, in the presence of an alkaline condensation agent such as sodium hydroxyl, is a strongly exothermic reaction. From aldol, crotonaldehyde is formed by removal of water. The reaction which occurs may be represented as follows:

One of the main difficulties encountered in effecting this reaction on an industrial scale, lies in the considerable release of heat in the production of aldol which must be carefully controlled to prevent a violent reaction. To assure the regular elimination of the heat, several methods have been suggested. There has been recommended especially the dilution of aldehyde by water, alcohol, etc., in order to reduce the speed of aldolizing and at the same time the speed of the secondary reactions which lead to the formation of the poly aldols. The efforts of the research workers have been mainly concerned with the means of refrigeration used; thus there has been recommended, for example, the use of plate heat ex-changers, having a very high heat exchanging coefficient.

Irrespective of the diversity of the devices evolved up to date, both for continuous and for interrupted operation, in using the known procedures one has always been forced to operate at the lowest possible economic temperature, so as to maintain the conversion at the upper limit. It is known that with high temperatures only a small percentage of conversion of acetaldehyde to aldol is effected.

In the processes known, the aldolizing was carried out either in strongly cooled vats or in countercurrent heat exchangers or in apparatus combining these two means. When the desired conversion degree had been obtained, the mixture was brought to a suitable pH to stop the reaction and it was conveyed to a distillation column in order to separate the excess acetaldehyde from same. Thereafter, the aldol was recovered and from it crotonaldehyde could be made. These prior processes were expensive to operate and uneconomical.

The principal object of the present invention accordingly is to provide a simple process which

2

shall do away, at least in part, with the disadvantages mentioned of the prior processes. Another object of the invention is to provide a process of the kind described which may alternatively produce either aldol or crotonaldehyde as desired and in which the crotonaldehyde may be produced directly from the aldol as a continuation of the process for producing aldol without necessity for isolating the aldol to produce such crotonaldehyde. Another object of the invention is to provide a simple apparatus which may be used for carrying out the process.

be used for carrying out the process.

The invention accordingly comprises the novel apparatus and combinations thereof, as well as the novel processes and steps of processes which may be carried out in such apparatus, specific embodiments of which are described herein by way of example only and in accordance with the manner in which I now prefer to practice the invention.

20 vention.
I have found in accordance with my invention
that operating at a low temperature is not indis-
pensable and that it is, on the contrary, im-
portant to operate at a high temperature. The
25 present invention, based on this surprising ob-
servation, is characterized by the fact that the
aldolizing is carried out in a medium at boiling
point. The vapors emitted consisting mostly of
30 acetaldehyde assure the regular release of the
heat generated during the reaction. It suffices
to conduct them into a condenser and to return
the condensed product to the apparatus.

35 An essential feature of this invention is that I effect conversion of ethanal to aldol in a body of liquid medium mainly comprised by ethanal, i. e. a volatile substance, so that a considerable amount of ethanal is vaporized by reaction heat and thus acts as a cooling fluid that carries heat to the condenser, and then is refluxed as a cool liquid. In other words, through the reaction zone and a condenser I provide a cycle of ethanal, whereby instead of using only the specific heat of the cooling agent as has been done for example where water was employed as a cooling agent, I use the total heat including the latent heat of evaporation so that for a given amount of cooling fluid, the latter is used much more efficiently. Hence it is possible according to the preferred embodiment of my invention to provide an aldolization zone of so small a volume that an adequately efficient heat exchanger for cooling purposes as conventionally employed in the past could not be accommodated therein.

According to another essential feature of this
invention, I make provision whereby acetalde-

hyde is in contact with aldolization catalyst only for a very short period of time, specifically not longer than about 5 minutes. For this purpose, in a reaction zone I maintain a shallow body of liquid mainly composed of acetaldehyde in major proportion and acetaldol in minor proportion, for example by providing a weir or overflow in a reaction chamber or by providing a number of capless trays in the top zone of a distillation column, and I continuously supply this shallow body of liquid with acetaldehyde at a rate of at least twelve times the volume of said body per hour, together with an alkaline aldolization catalyst in such a proportion as to cause conversion of about 35 to 15 per cent of acetaldehyde to acetaldol; with such a rate of conversion, heat developed by the aldolization reaction keeps the body in steady, strongly boiling condition at a temperature of about 30 to about 45° C., producing a considerable evolution of acetaldehyde vapors which provide for dissipation of heat produced in the body. The liquid which overflows from said body still contains aldolization catalyst, which I thereafter immediately render ineffective, e. g. by adding acid.

The period of contact is preferably from 1 to 5 minutes and consequently the rate of supply of liquid acetaldehyde to the body of liquid per hour should be from about 60 to about 12 times the volume of said body.

According to the preferred embodiment of my invention, the vapors of acetaldehyde evolved from the boiling body of liquid are condensed in a separate condensation zone; furthermore unconverted acetaldehyde in the liquid overflowing from the body is recovered, and the condensed acetaldehyde, the reconnected acetaldehyde and a proper amount of fresh acetaldehyde are combined to form the aforesaid supply of acetaldehyde to said body; the proportion of fresh acetaldehyde in the supply of acetaldehyde continuously fed to the body is from about 23 to about 12.5 per cent with respect to the total supply where a rate of conversion of 35 to 15 per cent is secured. As to the proportion of alkaline aldolization catalyst with respect to fresh acetaldehyde, it amounts to about 0.2-0.3 per cent expressed in terms of caustic.

As stated, the process is preferably operated in a continuous manner. It includes the maintenance of a shallow body, preferably shallow pools of liquid, contained in an aldolizing chamber and which liquid consists mainly of acetaldehyde in major proportion and acetaldol in minor proportion. This chamber constitutes a reaction zone which has a greater volume than the total volume of the pools. Liquid acetaldehyde is fed to the uppermost of these pools and it overflows to the next pool below, the depth and consequently the volume of the liquid in any pool being controlled by the height of the overflow above the bottom of the pool. The rate of feed of the acetaldehyde is at least 12 times the total combined volume of the pools per hour. To the uppermost or first pool, an aldolization catalyst is fed in a proportion to cause conversion of about 35-15% of the acetaldehyde fed to the first pool. The pools are kept in a strongly boiling condition at a temperature of about 30 to 45° C. The acetaldehyde is constantly boiled off, condensed and returned to the aldolizing chamber. The rate of flow of freshly supplied acetaldehyde plus that recycled is equal to at least 12 times the volume of liquid in the pools of the aldolizing chamber. The rate of sup-

ply of fresh acetaldehyde is about 12.5 to 23% of the combined total of acetaldehyde recycled and acetaldehyde freshly added. An aldolization catalyst is added to the shallow body of liquid at a rate of about 0.2 to 0.3% with respect to the rate of supply of acetaldehyde.

Thus, where there is approximately 40 liters of liquid on the capless plates in chamber 1 as discussed below in connection with the drawings, the acetaldehyde is supplied at a rate of at least 480 liters per hour and the aldolization catalyst is supplied at a rate of about at least 9.6 to about 14.4 liters per hour.

To replace the aldolizing equipment heretofore used and the consequent complex refrigerating circuit, it suffices in accordance with my invention, to provide a simple aldolizing chamber connected with the aldol-acetaldehyde separation column in such a manner that the vapors which carry off the calories of the reaction and which are emitted during the aldolizing, join the vapors originating from the column while the condensed liquid passes through the aldolizing zone or chamber and thence to the column. In both of the apparatuses described below, the acetaldehyde is in an enclosed circuit and losses are consequently cut down.

In the accompanying drawings is shown an apparatus in accordance with my invention which may be employed to carry out my above described process, in which

Figure 1 represents a diagrammatic elevation showing in cross section a column of which the upper portion constitutes the reaction chamber, and

Fig. 2 shows a similar elevation of a modified device in which a separate reaction chamber is used.

Referring now to these drawings, the numeral 1 represents an aldolizing chamber containing plates 2. These plates are provided with the customary overflows 3 which permit the flow of liquid from plate to plate but instead of being provided with bubble caps, they are provided with uncapped flues 4 and 5 which permit the free passage to a condenser 7 of all vapors originating in the aldolizing chamber and in the column below. With these vapors flows heat from the exothermic reaction, thus preventing excessive rise of temperature in the reacting mixture. These vapors may then flow freely through the conduit 6 at the top of the chamber to the condenser 7 and upon condensation may be returned through pipe 8 to the chamber above the uppermost plate 2.

This aldolizing chamber 1 is placed directly on top of the separating column 9 which is provided with the usual plates 10 and also provided with the usual overflows 11. Each of the plates 10 has the usual central flue 12 provided with a bubble cap 13.

Liquid collecting at the base chamber 14 of the column 9 may be heated by a steam coil 15 to the boiling point and removed through conduit 15a controlled by valve 16.

A supply of acetaldehyde and water is fed through pipe 17 to pipe 3 and thus passes into the aldolizing chamber along with condensate from the condenser 7. Through a pipe 18 a solution of an alkaline agent, as sodium, potassium or barium hydroxide is fed onto the uppermost plate 2 of the aldolizing chamber. Through a pipe 19, acetic acid or other neutralizing agent, as sulphuric, phosphoric or hydrochloric acid, is passed onto the uppermost plate

of the separating column 9. The system may be put under pressure of nitrogen or other inert gas by admitting same through a pipe 20 which admits such gas under pressure through pipe 8. Admission of nitrogen is controlled by a valve 20a. The source of nitrogen or other inert gas is not shown in the drawings.

In Fig. 2, a modification is shown. The aldolizing chamber 1 consists of a vat which is separate from the separating column 9. Other than this separate chamber and its connections, the characteristics of Figs. 1 and 2 are substantially the same. It is connected with the uppermost plate 10 of the separating column by a pipe 21. Water and acetaldehyde are admitted through pipe 17 and sodium hydroxide is admitted through pipe 18. These pipes join pipe 8 which return condensate from the condenser 7 to the aldolizing chamber. A pipe 22 leads directly from the top of the separating column 9 to the condenser 7. It is joined by the pipe 6 leading from the aldolizing chamber 1 and through it pass the acetaldehyde vapors from both the chamber 1 and the column 9.

The following are examples of my process. These examples are illustrative and the process is not to be restricted thereto except as indicated in the appended claims.

Example 1

107 kgs. per hour of acetaldehyde and 20 kgs. per hour of water are introduced through pipe 17 into the top of the aldolizing chamber 1 flowing in over the top plate 2. 16 liters of aqueous sodium hydroxide containing 20 grams of NaOH per liter are introduced through pipe 18 to mix with the water and acetaldehyde above the plate 2.

An exothermic reaction occurs as the aldolizing is effected in the aldolizing chamber. The mixture of acetaldehyde, water and sodium hydroxide overflows through pipes 3 from each of the two plates 2 in this chamber and descends to the uppermost plate 10 of the separating column 9. The aldolizing is effected on the plates 2 of the aldolizing chamber and the flow of material over these plates is regulated in such a manner that the liquid held by them remains there for about five minutes. The heat released by the reaction causes the liquid to boil at about 33° C. The vapors consisting substantially of pure acetaldehyde escape from the column through pipe 6, are condensed at 7 and returned to the uppermost plate 2 of the aldolizing chamber through pipe 8.

From the lowermost plate 2 of the aldolizing chamber, liquid passing onto the plate 10 is a mixture of about 107 kgs. per hour of aldol, 320 kgs. per hour of acetaldehyde and 36 kgs. of water.

In this example, the volume of the body of liquid or pool on the capless plates in chamber 1 amounts to about 40 litres, and its free or exposed surface has an area of about 4 square decimeters; it should be understood that the foregoing figures are not limitative (thus for example an area larger than 4 square decimeters may be provided) but they readily show that I can effect aldolization efficiently in a quite small reaction chamber.

Acetic acid of 50 grams per liter is introduced through pipe 19 onto the uppermost bubble plate 10 of the separating column at the rate of about 16 liters per hour. Acetic acid neutralizes the mixture and brings its pH to a value of between about 4 and about 5. This causes the aldol reaction to stop. The separation of the acetaldehyde and aldol formed is effected on the succeed-

ing plates 10 of the separating column. The liquid collecting in the base chamber 14 of the separating column is heated by steam passing through pipe 15 and is accordingly maintained at its boiling point. It consists of a solution of aldol with the diluent water and sodium acetate. This mixture is drawn off at the base of the column through the pipe 11 and the aldol is recovered from the mixture in a known manner. The yield of aldol is approximately 97%.

The above process is carried out at atmospheric pressure. It may also be carried out at a slightly higher pressure, namely, about .5 kg./cm.² above atmospheric pressure, in order to facilitate the condensation of the vapors of acetaldehyde. For this purpose, nitrogen or other inert gas may be introduced through the pipes 20 and 8 in regulated amount to give the desired pressure. The liquids then introduced through the pipes leading to the aldolizing chamber 1 and to the fractionating column 9 are then admitted under suitable pressure. The gate valve 16 regulates the release of the aldol-containing liquid from the chamber 14.

25 Crotonaldehyde may be directly manufactured from aldol thus formed without isolating the aldol. For this purpose, a pressure from 1 to 5 kg./cm.² is maintained throughout the apparatus. This pressure results in uniformly increasing the 30 entire range of temperatures prevailing throughout the apparatus, thus causing the dehydration of aldol in the separating column 9 to form crotonaldehyde. In other words, using exactly the same number of plates with the increased pressure, the product accumulating in the base chamber 14 of the separating column 9 will be crotonaldehyde instead of aldol.

It is more convenient in the case of an apparatus as shown in Fig. 2 to cause the superatmospheric pressure suitable for crotonisation purposes to be set up only in the distillation zone 9, by providing pressure retaining means in pipes 21 and 22, so that aldolization proper in chamber 1 may be effected under atmospheric pressure or 45 an only slightly increased pressure.

Example 2

I introduce through pipe 17 and thence into the aldolizing chamber 107 kgs. per hour of acetaldehyde, and through pipe 18 I introduce 14 50 l. of aqueous potassium hydroxide solution containing 30 grams of KOH per liter. Note that no water need be introduced with the acetaldehyde for the manufacture of crotonaldehyde. The mixture remains in the aldolizing chamber about 4 minutes. A pressure of approximately 2 kgs./cm.² is maintained throughout the apparatus. Onto the top plate 10 of the separating column there flows a mixture of 107 kgs. per hour 60 of aldol, 320 kgs. per hour of acetaldehyde and 14 l. of water. This mixture is neutralized by phosphoric acid and its pH is brought to a value of between about 4 and about 5 by a solution of such acid of 60 grams per liter introduced 65 through pipe 19 at the rate of 14 liters per hour. The crotonaldehyde formed in the column 9 by dehydration of aldol in acid medium under pressure, accumulates in the base chamber 14 under hydrated condition due to the presence of the 70 dehydration water and may be drawn off through the gate valve 16. The length of time in which the aldol flows over the plates and in the base chamber 14 under the above conditions is about 30 minutes to form crotonaldehyde. The crotonaldehyde may be recovered from the mixture 75

flowing from the base chamber 14 in a known manner.

Instead of increasing the pressure, the number and/or capacity of the plates of the separating column may be increased in order to increase the time in which the aldol in the pot remains in the acid medium, which also causes the formation of crotonaldehyde.

Instead of employing a pressure of 2 kgs./cm.², a greater number or capacity of plates may be employed with a slightly elevated pressure, say, 1 kg./cm.².

It is also possible to draw off crotonaldehyde in the form of a vapor consisting of an azeotropic mixture thereof with water. This may be done through the pipe 22 located a few plates above the base chamber 14. Under these circumstances, residual liquors consisting of practically pure water flow off through pipe 11.

What I claim is:

1. In a continuous process for the production of acetaldol, continuously feeding acetaldehyde and acetaldol catalyst into a shallow body of liquid largely composed of a mixture of acetaldehyde and acetaldol and containing an acetaldol catalyst in a reaction zone of greater volume than said body, thereby producing an exothermic reaction between acetaldehyde and catalyst causing the mixture to boil strongly, retaining the fed liquid in the reaction zone for a period of not over 5 minutes approximately at a temperature of from 30-45° C., converting about 35 to 15% of the acetaldehyde to acetaldol, continuously withdrawing at a temperature not exceeding 45° C. acetaldol, acetaldehyde and unspent catalyst from the reaction zone and rendering the unspent catalyst ineffective.

2. A process in accordance with claim 1 in which the acetaldol catalyst is a caustic alkali and is supplied at a rate of about 0.2 to about 0.3% with respect to the fed acetaldehyde.

3. In a continuous process for the production of acetaldol, maintaining a succession of constant volume shallow pools of liquid composed principally of a mixture of acetaldehyde and acetaldol and containing an acetaldol catalyst, in a reaction zone of greater volume than the total volume of said pools, continuously feeding acetaldehyde and acetaldol catalyst through the first pool so as to cause the same to pass through the successive pools, causing the liquid in the pools to boil strongly, retaining the fed liquid in the reaction zone for a period of not over five minutes approximately at a temperature of from 30-45° C., converting about 35% to 15% of the acetaldehyde to acetaldol, continuously withdrawing from the reaction zone at a temperature not exceeding 45° C. acetaldol, acetaldehyde and unspent catalyst, and rendering the unspent catalyst ineffective.

4. A continuous process for the production of acetaldol which comprises, maintaining a shallow body of liquid having an overflow controlled constant volume, said liquid being mainly composed of acetaldehyde in major proportion and acetaldol in minor proportion in a reaction zone having a greater volume than said body, continuously supplying fresh liquid acetaldehyde and an acetaldol catalyst to said body, said catalyst being supplied at a rate of about 0.2 to about 0.3% with respect to the fresh acetaldehyde supplied,

maintaining the body thereby in a strongly boiling condition at a temperature of 30 to 45° C., leading acetaldehyde vapors from the reaction zone to a condensation zone, retaining the body of liquid in the reaction zone for a period of not over five minutes at the boiling temperature of 30 to 45° C., converting about 35 to 15% of the acetaldehyde to acetaldol, continuously withdrawing at a temperature not exceeding 45° C. the liquid acetaldol, acetaldehyde and unspent catalyst from the reaction zone, rendering the unspent catalyst ineffective, distilling acetaldehyde from the withdrawn liquid and condensing same in said condensation zone, and returning acetaldol continuously to the reaction zone along with said fresh acetaldehyde.

5. A continuous process for the production of acetaldol which comprises, maintaining a shallow body of liquid having an overflow controlled constant volume, said liquid being mainly composed of acetaldehyde in major proportion and acetaldol in minor proportion in a reaction zone having a greater volume than said body, continuously supplying fresh liquid acetaldehyde and an acetaldol catalyst to said body, said catalyst being a solution of caustic alkali and being supplied at a rate of about 0.2 to about 0.3% with respect to the fresh acetaldehyde supplied, maintaining the body thereby in a strongly boiling condition at a temperature of 30 to 45° C., leading acetaldehyde vapor from the reaction zone to a condensation zone, retaining the body of liquid in the reaction zone for a period of not over five minutes and approximately at the boiling temperature of 30 to 45° C., converting about 35 to 15% of the acetaldehyde to acetaldol, continuously withdrawing at a temperature not exceeding 45° C. the liquid acetaldol, acetaldehyde and unspent catalyst from the reaction zone, continuously adding acid to the liquid thus withdrawn to bring the pH value thereof to about 4 to 5, continuously distilling the acidified liquid in a distillation zone, to expel unconverted acetaldehyde contained therein as vapors, continuously condensing the last named vapors in said condensation zone to obtain liquid acetaldehyde, and continuously returning the liquid acetaldehyde obtained in the condensation zone to said body.

6. A process in accordance with claim 1 in which the process is effected under an inert gas pressure of zero to 0.5 kg. per square centimeter above atmospheric pressure.
